R. P. MYERS, B. F. ROUSE, AND JAMES M. OSBORN, OF CLEVELAND, OHIO.

Design No. 3,763, dated November 23, 1869.

DESIGN FOR A STOVE.

The Schedule referred to in these Letters Patent and making part of the same

---

We, R. P. MYERS, B. F. ROUSE, and JAMES M. OSBORN, of Cleveland, in the county of Cuyahoga, and State of Ohio, have invented and produced a new and original Design for Stoves, of which the following is a specification.

The nature of our design is fully represented in the accompanying photographic illustration, to which reference is made.

The doors of the stove (which we call the "Chieftain") here referred to contain the new configuration of design, which consists of a raised border of half-round knobs, arranged in a straight line on a raised strip, near the edge of the door-plates.

The central figure is a large ornament, oval in form, and covering a greater portion of the surface of the

door, and consists of a scroll-border, connected at the top, bottom, and sides by a leaf, in relief, the central portion raised, in form of a plain oval, and having a series of lines radiating from it to the scroll-border.

Within the plain oval is a carved scroll, having four points, with a cross connecting the points.

The surface within the plain oval is convex.

We claim, as our invention, the design for a stove, as shown.

R. P. MYERS.
B. F. ROUSE.
JAMES M. OSBORN.
